MULTIPLE GAS BURNER FOR TIPPING-OFF GLASS ARTICLES

Filed Aug. 15, 1946

FIG. 1

FIG. 2

INVENTOR:

PAUL O. CARTUN,
BY *John H. Anderson*
HIS ATTORNEY

UNITED STATES PATENT OFFICE

2,571,537

MULTIPLE GAS BURNER FOR TIPPING-OFF
GLASS ARTICLESPaul O. Cartun, Cleveland Heights, Ohio, assignor
to General Electric Company, a corporation of
New York

Application August 15, 1946, Serial No. 690,814

2 Claims. (Cl. 158—104)

1

This invention relates to apparatus for manufacturing electric lamps and similar articles and more particularly to burners used for tipping-off and hermetically sealing evacuated or gas filled lamp bulbs.

An object of my invention is to provide a new and improved gas burner.

Another object of my invention is to provide a device or burner which may be used for the expeditious and automatic performance of a tipping-off operation.

A further object of my invention is to provide a gas burner which will operate to locally heat a portion of an exhaust tube to sever the same from the bulb and automatically discharge the waste section of the exhaust tube from the burner.

Further features and advantages of my invention will appear from the following detailed description of species thereof.

For a better understanding of my invention reference may be had to the following description taken in connection with the accompanying drawings and its scope will be pointed out in the appended claims.

Fig. 1 is a side elevation, partly in section, of the tipping-off burner incorporating my invention.

Fig. 2 is a sectionalized view showing more in detail the tipping-off burner incorporating my invention.

Referring to Fig. 1 the tipping-off device therein comprises a burner head or support base 1 having elongated hollow arms 2 which may be for example detachable threaded hollow tubes or sleeves 2 having burner manifolds 3 extending parallel to each other and coextensive. Facing sides of arms 2 each have a plurality of passageways communicating with the hollow interior of arms 2 to provide burner openings 4. These burner openings 4 may be for example four, one thirty second inch openings, or jets positioned at a forty-five degree angle to the longitudinal axis of the hollow burner arms 2 and at a ninety degree angle to each other. The size of the burner openings, however, varies with the type of glass used. In this manner a sheet of flame is directed toward the center of the burner. Although the drawing indicates that the burner openings 4 are on a horizontal plane parallel with that of the burner arms, obviously the invention includes variation in which the openings are not on this horizontal plane. The burner arms 2, for example, may be formed as indicated in Fig. 2 with grooves or notches 5 providing

2

beveled or flaring out sides 6 embodying the burner openings 4.

The notches 5 are elongated along the arms 2 and, as will be apparent from the drawing, the beveled sides 6 are substantially equidistantly spaced apart within each notch 5 and between the opposed notches 5 so as to lie substantially at the corners of a square, the jet openings 4 being directed along the diagonals of said square toward a common center. The burner head 1 has an article supporting bracket 7 terminating in an annular seating collar portion 13 is alignment with the common center toward which the jet openings 4 are directed for positioning a vessel with its vitreous exhaust tube transverse to and between the burner arms 2 and in sealing relationship to the burner. A vessel 8 with a base 9 and a vitreous exhaust tube 10 is indicated in Fig. 1 to show the relative position of vessel, base, and tube to the burner. The seating collar portion 13 has a gap 14 in the side thereof toward the distal closed ends of the arms 2 for passage of the tube 10 laterally therethrough and between the arms 2. Burner head 1 is also provided with a conduit 11 for connecting a gas supply to the burner head and to communicate with the hollow interior of the burner arms 2.

Fig. 2 is a sectionalized view showing more in detail the tipping-off burner of Fig. 1 and incorporates the above described corresponding parts of Fig. 1. This view also shows in detail one means of seating the burner arms 2 and gas supply conduit 11 in the burner head 1 in order to provide a gas passageway 12 from the gas supply conduit 11 through the burner head 1 and into the burner arm manifolds 3.

In accordance with my invention I provide a tipping-off burner which will regulate, check, expand and direct a current of gas to the position where it becomes admixed with the requisite amount of atmospheric air for perfect combustion. Accordingly I provide a burner directly fed from burner arm manifolds which checks, expands, and directs a current of gas to the nozzles or jets 4 of the burner. Thus, by means of the burner arm manifolds a stream of properly expanded gas, at a low pressure, without disturbing currents, becomes available for combustion. The burner operates to locally heat a portion of an exhaust tube to sever the same from the bulb and automatically discharge the waste section of the exhaust tube from the burner.

Generally speaking, I effect these desired results by means of a burner head which provides elongated hollow burner arms which serve as

burner manifolds of large enough capacity to properly expand, direct and regulate the current of gas and produces this gas at jets or burner openings designed to locally heat a portion of a vitreous exhaust tube to sever it therefrom. The burner tends toward expeditious and automatic performance of a tipping-off operation by providing an article supporting bracket 7 which may be automatically loaded and unloaded, and the waste evacuated in preparation for a repeat performance.

What I claim as new and desire to secure by Letters Patent of the United States is:

1. A gas burner comprising a hollow head portion having a pair of parallel, hollow arms extending therefrom, communicating therewith, spaced a small distance apart and having closed distal ends, the walls of the facing sides of said arms being provided adjacent their closed distal ends with opposed notches elongated along the length of the arms and having beveled sides and jet openings in said beveled sides communicating with the hollow interior of said arms, the said beveled sides being substantially equidistantly spaced apart so as to lie substantially at the corners of a square, said jet openings having their axes at substantially forty-five degree angles to the longitudinal axes of said arms and at substantially a ninety degree angle to each other to direct gas jets radially toward a common center, and a conduit for connecting a gas supply to said burner head and communicating with the hollow interior of said arms.

2. A gas burner comprising a block-shaped head portion having spaced openings in a face thereof, a gas supply opening in another face thereof and a passageway connecting the sup-

ply opening with each of said spaced openings, a pair of parallel hollow arms secured in said openings in communication with said passageway and closed at their distal ends, opposed wall portions of said arms adjacent their distal ends each having therein a notch elongated along the arm and having beveled sides having jet openings therethrough to the interior of the respective arms, the said beveled sides being substantially equidistantly spaced apart so as to lie substantially at the corners of a square, and said jet openings being directed along the diagonals of said square toward a common center between said arms.
